UNITED STATES PATENT OFFICE

171,568

COMBINATION ELECTRIC VIBRATORY
SANDER AND POLISHER

Nicholas Anton, Park Ridge, Ill.

Application August 31, 1953, Serial No. 26,633

Term of patent 14 years

(Cl. D9—2)

To all whom it may concern:

Be it known that I, Nicholas Anton, a citizen of the United States, residing at Park Ridge, in the county of Cook and State of Illinois, have invented a new, original, and ornamental Design for a Combination Electric Vibratory Sander and Polisher, of which the following is a specification, reference being made to the accompanying drawings forming a part hereof.

In the drawing:

Fig. 1 is a front perspective view of a combination electric vibratory sander and polisher embodying my new design;

Fig. 2 is a side elevational view of the sander and polisher shown in Fig. 1;

Fig. 3 is a top plan view of the sander and polisher shown in Fig. 1;

Fig. 4 is a front elevational view of the sander and polisher shown in Fig. 1; and

Fig. 5 is a rear elevational view of the sander shown in Fig. 1.

The cord is shown broken away in Figs. 2, 3 and 5, for convenience of illustration.

I claim:

The ornamental design for a combination electric vibratory sander and polisher, substantially as shown.

NICHOLAS ANTON.
